UNITED STATES PATENT OFFICE.

EDWARD HATCH, OF PORTLAND, OREGON, ASSIGNOR TO FRED A. DOUTY, OF PORTLAND, OREGON.

BUNDLING-MACHINE.

1,300,166.

Specification of Letters Patent.

Patented Apr. 8, 1919.

Application filed June 29, 1917. Serial No. 177,711.

To all whom it may concern:

Be it known that I, EDWARD HATCH, a citizen of the United States, and resident of Portland, in the county of Multnomah and State of Oregon, have invented certain new and useful Improvements in Bundling-Machines, of which the following is a specification.

This invention relates to bundling machines and has more especial reference to an improved wire twisting and tying machine.

The invention has for its dominant object to provide a wire twisting and tying machine for use in bundling operations, whereby, the ends of a tying wire or like strand will be positively connected by twisting the same upon each other, thus, providing a strong and durable bond therebetween.

It is a more specific object of the invention to provide a machine of the character mentioned whereby various objects can be arranged in piles, a tying wire being passed thereabout, compressed, and the ends of the tying wire positively connected by twisting, and upon completion of the twisting operation, the tying wire then severed from the feed strip and released together with the bundle.

Another object of the invention is to provide novel means for compressing the matter to be bundled and holding the same compressed during the tying of the wire, whereupon it is released for removal from the machine.

Still another object of the invention is to provide a machine with means whereby the tying wire ends will be securely held thereby during twisting of the same but when twisted will be automatically released.

Other independent objects are to provide features of construction of portions of the machine which tend toward the attainment of the above aims irrespective of the relation in which they are used.

Other objects will be in part obvious and in part pointed out hereinafter.

The invention accordingly consists in the features of construction, combinations of elements, and arrangement of parts which will be exemplified in the construction hereinafter set forth, and the scope of the application of which will be indicated in the following claims.

In the accompanying drawings, wherein is

shown one of various possible embodiments of my invention.

Figure 1 is a top plan of the bundling and tying machine;

Fig. 2 is a fragmentary side elevation thereof;

Fig. 3 is a detail in side elevation of the wire twisting and tying head of the machine;

Fig. 4 is a fragmentary longitudinal section through the said head;

Fig. 5 is a front elevation of the head;

Fig. 6 is a disassembled detail in perspective showing the wire twisting and tying means or jaws of the machine head;

Fig. 7 is a detail in perspective of means for securing one end of the tying wire during the twisting of its ends;

Fig. 8 is a fragmentary detail in section of a latch for the securing means;

Fig. 9 is a section taken at right angles to the Fig. 8, and

Fig. 10 is a fragmentary detail in perspective showing the means for actuating the bundle compressing means of the machine.

Similar reference characters refer to similar parts throughout the several views of the drawings.

Having more particular reference to the drawings the improved machine includes a frame designated in its entirety by the numeral 1. A supporting pillar 2 is arranged in proximity of one of the corners of the frame 1 and serves as means for supporting the wire twisting and tying head hereinafter more fully described. Supporting bars 3 having their upper ends secured to the upper end of the pillar 2 and their lower ends to the frame adjacent its corners are provided, and as will be noted, one of the same serves to support a wire receiving and feeding reel 4, this reel being rotatably supported upon a suitable table.

A combined guard and guide plate 5 is secured to the supporting pillar 2 and has its lower extremity bifurcated as indicated at 6 whereby the laterally extending fingers of a bundle supporting rack 7 may be slidably received therebetween; this rack 7 being in turn secured to the upper end of a standard 8 formed of squared metal and having its lower end provided with a series of openings 9. The lower end of the squared standard 8 is slidably received through a guide

member or bracket 10 arranged upon the adjacent leg of the frame 1. Slidably on the lower extremity of the standard 8 is a collar 11 having an opening 12 formed in one side 5 thereof, this opening being surrounded by a boss or enlarged portion 13 whereby a locking pin 14 may be passed through the collar into engagement with any one of the series of openings 9 formed in the standard. 10 Obviously, by slidably arranging the collar 11 upon the lower end of the standard 8, its position thereupon may be varied and locked by passing the pin 14 through the selected opening 9. Upon another of the sides of the 15 collar 11 there is formed a ratchet face 15 which is adapted to be engaged by a pawl 16 pivotally supported upon a shaft 17 mounted in suitable supports arranged upon the frame 1. A second shaft 18 is arranged in 20 proximity to the shaft 17 and carries thereon a cam 19, which cam is positioned adjacent the pivotal pawl 16 and has bearing thereon at times for a purpose which will be herein-after more fully described. As means for 25 elevating the bundle receiving rack 7 together with its standard 8 a foot lever 20 is pivotally supported upon a diagonally disposed bracing strip 21 secured to one side of the frame 1 and that leg of the same adjacent the standard 8. An offset portion 22 is formed upon the foot lever 20 adjacent its point of fulcrum and has bearing upon the lower end of a collar 11 slidably arranged on the standard 8. Thus, when the foot lever 25 20 is depressed the collar 11 will be moved upwardly and should this collar be connected to the standard 8 through the medium of the locking pin 14 the said standard together with the rack 7 will be elevated, and as a 30 consequence, the bundle arranged thereon compressed. The bundle will be maintained in its compressed state upon the rack 7 due to the engagement of the pivotal pawl 16 with the ratchet plate 15 formed on the collar 11 until it is desired to release the same. 35 To the upper end of the supporting pillar 2, which as will be noted, is provided with a bracket 23, a head 24 is secured, this head comprising a plurality of oppositely disposed plates, the forward lower portions of which are provided with openings wherein wire receiving and twisting means comprising rotatable jaws 25, 26 and 27 may be mounted. As will be noted, these rotatable 40 jaws have gear teeth disposed about portions of their periphery to facilitate the rotation thereof. A pinion 28 is in mesh with the gear teeth of the rotatable jaw 25 and is in turn engaged by a segment 29 mounted upon 45 a shaft 30 journaled in suitable bearings in the head 24, this shaft having keyed thereto an operating handle 31, the lower extremity of which is bifurcated and straddles the said head in order that proper engagement with the shaft 30 may be effected. Obviously, 50 by rocking the operating handle 31 rotary motion will be imparted to the rotatable jaw 25 through the medium of the gearing designated by the numerals 28 and 29. Another shaft 32 is journaled between the plates of 55 the head 24 and has keyed to its opposite end segments 33 which mesh with the gear teeth arranged about the peripheries of the rotatable jaws 26 and 27, one of the segments 33 being provided with a bifurcated extension 60 34 which has pivotally connected thereto an operating rod 35 pivotally connected to the lower end of a tripping arm 36 as at 37, the said tripping arm having a way 38 formed therein, the upper end of which is curved so 65 as to cause a reciprocatory movement to be imparted to the rod 35 upon the rocking of the handle 31; it being noted in this connection that the shaft 30 to which the handle is secured has keyed thereto an arm 39 carrying a roller upon its lower end, this roller being receivable in the way 38 of the trip 36. 70 To one side of the head 24 in proximity to the rotatable jaw 26 there is pivotally mounted a jaw 40, this jaw having movement over a second and stationary jaw 41. Upon the opposite side of the head 24 and in proximity to the rotatable jaw 27 a wire cutter 42 is pivotally mounted, a lever 43 being formed upon one side thereof and being normally maintained in an inoperative position by means of a contractile coil spring 44 having one end engaged therewith and its opposite end with the shaft 32. To operate the pivotal jaw 40, a bar 45 is slidably received through a recess formed therein, and has a wedge-shaped portion formed upon that end adjacent the said jaw while a lug 46 is formed upon the opposite end and is adapted to be intermittently engaged by a 75 tripping leg 47 also keyed upon the shaft 30 and operated through movement of the handle 31. Thus, when the bar 45 is moved forwardly due to its engagement with an expansible coil spring 48, the pivotal jaw 40 80 100 will be released and permitted to securely engage one end of the tying wire between the same and the immovable jaw 41. However, upon operation of the handle 31 and engagement of the tripping leg 47 with the lug 46 the bar 45 is now moved in an opposite direction causing the wedge-shaped portion formed thereon to force the pivotal jaw 40 outwardly and as a consequence, release the end of the tying wire previously secured 105 thereby. To operate the wire cutter 42 upon completion of the twisting or tying of the ends of the wire, a tripping leg 49 is keyed upon the ends of the shaft 30 opposite to the mounting of the tripping leg 47 and obviously is engaged with the adjacent end of the lever 43 upon the completion of the downward movement of the said operating handle 31. 110 Directly adjacent the rear side of the piv- 115 120 125 130

otal jaw 40 a latch 50 is pivotally mounted upon an adjacent portion of the head 24 and is normally maintained under tension by means of an expansible coil spring 51, there-
5 by engaging a boss carried by the said latch with the recess formed upon the rear side of the pivotal jaw 40. Thus, the jaw 40 will be maintained in an open position subsequent to the releasing of the tying wire end 10 therefrom; a finger-piece 52 being formed upon the lower end of the latch 50 to facilitate disengagement of the same with the pivotal jaw when it is desired to again engage one end of a tying wire thereby. To 15 limit outward movement of the pivotal jaw an arm 53 is secured to the head 24 and has its free end lying in proximity to the outer edge of the said pivotal jaw.

Pivots supported upon the pillar 2 and 20 movable over a segment 54 which is secured to the upper end of the supporting pillar 2 is a wire stretching lever 55, this lever having oppositely disposed pivoted pawls 56 mounted upon its upper face and adapted to 25 receive the free end of the tying wire therebetween; this end of the tying wire leading to the supply bundle arranged upon the rotatable reel 4. Thus, by rocking the lever 55 when the free end of the tying wire has 30 been engaged between the pivoted pawls 56 the same may be drawn tightly about the matter to be bundled, previous to the twisting thereof. It is to be also noted, that the pivoted pawls 56 carried by the wire stretching 35 lever are so arranged as to cause the free end of the tying wire to be passed beneath the wire cutter 42 in order that it may be severed from the feed strip upon completion of the tying or twisting operation.

40 An operating rod 57 is arranged vertically of the machine and has its lower end connected to a lever 58 keyed to the shaft 18 and its remaining end pivotally connected to a bell crank lever 59 supported in bearings 60 upon the upper end of the pillar 2. A second tripping leg 61 is arranged upon the shaft 30 adjacent the tripping leg 49 and is engaged with the free end of the bell crank lever 59 upon completion of the move-
45 ment of the operating handle 31 during the twisting operation. By so operating the bell crank lever 59, that is, due to engagement of the tripping leg 61 therewith, the connecting rod 57 will be pulled upwardly thereby rotating the shaft 18 and causing the cam 19 to engage a portion of the pivoted pawl 16 and force the same outwardly out of engagement with the ratchet face 15 formed upon the slidable collar 11. With the pawl 16 50 thus disengaged the bundle rack 7 will be permitted to return to its lowermost or normal position and the tied bundle may be then readily removed.

The operation of the machine may be re-
60 viewed as follows: Matter to be bundled is

placed upon the rack 7 while it is in its lowermost position, a tying wire supplied by the bundle arranged upon the rotatable reel 4 having been previously passed thereabout. The free end of the tying wire is engaged between the movable and immovable jaws 40 and 41 while that end of the same coming from the supply reel 4 is passed over the cutting element 42 and between the pivoted pawls 56 of the wire stretching lever 55. 70 The collar 11 is now properly adjusted upon the standard 8 and the foot lever 3 is depressed to cause the compressing of the matter arranged upon the rack 7, said matter engaging the head 4. After compressing the 80 bundle the tying wire is drawn taut about the same by rocking the wire stretching lever 55. With preparations thus made the operating handle 31 is swung forwardly upon its shaft 30 causing the rotatable wire twisting 85 jaw 25, through which the opposite ends of the tying wire are passed, to be rotated, thereby twisting the straight ends of the tying wire upon themselves due to the fact that the outer portions of the ends are engaged by the jaws 26 and 27 which to this time are not rotated. Upon completion of the downward movement of the operating handle 31 the ends of the tying wire have been sufficiently twisted upon themselves to 90 insure a secure bond and reciprocatory movement is imparted to the rod 35 through the tripping arm 36 thus causing the segments 33 to be partially rotated whereupon the rotatable jaws 26 and 27 will be then moved 100 to position wherein the wire receiving slots formed therein will align with the wire receiving slot formed in the jaw 25. By so aligning the wire receiving slots of the various twisting jaws the now twisted ends of the 105 tying wire are released therefrom. Simultaneously with the rocking or oscillation of the segments 33 the tripping leg 49 is engaged with the lever 43 of the wire cutter 42, whereupon the tying wire is severed from 110 the feed strip arranged upon the rotatable reel 4. Further, the tripping leg 61 is engaged with the free end of the bell crank lever 59 and thereby causes the cam 19 to 115 disengage the pawl 16 from the ratchet plate 15 of the collar 11 in order that the rack 7 supporting the bundle will be permitted to move to its lowermost position. At this time, the bundle can be readily removed from the machine and other matter to be bundled 120 placed upon the rack 7 thereof.

I claim:

1. In a bundling machine, a frame, article supporting and compressing means, wire receiving and feeding means, a head on the frame, wire holding and twisting means on the head, means for operating the holding and twisting means, other means operable by said operating means subsequently to the twisting of the wire for severing the same 130

from the feeding means, and other means for releasing the twisted wire from the holding and twisting means.

2. In a bundling machine, a frame, article supporting and compressing means, wire receiving and feeding means, a head on the frame, a rotatable wire twisting jaw on the head, wire receiving jaws arranged on the opposite side of said twisting jaw, means for 5 rotating said twisting jaw, other means engageable with said rotating means for causing rotation of said receiving jaws subsequently to rotation of the twisting jaw, and a wire cutter operable subsequently to the 10 twisting of the wire for severing the same from the feeding means.

3. In a bundling machine, a frame, article supporting and compressing means, rotatable wire receiving and feeding means, a 20 head on the frame, a rotatable wire twisting jaw journaled in said head, rotatable wire receiving jaws journaled upon the opposite sides of said twisting jaw, wire securing means arranged adjacent one of said receiving 25 jaws, means for causing rotation of the wire twisting jaw, means engageable by said rotating means for causing rotation of the receiving jaws, and further means operable by said rotating means for releasing the wire 30 securing means subsequently to the twisting of the wire.

4. In a bundling machine, a frame, article supporting and compressing means, rotatable wire receiving and feeding means, a 35 head on the frame, a rotatable wire twisting jaw journaled in said head, other rotatable wire receiving jaws journaled upon the opposite sides of the twisting jaw, means mounted adjacent one of said receiving jaws 40 for securing an end of the wire, a wire cutter mounted adjacent the opposite receiving jaw, manually operable means for causing rotation of said twisting jaw and then rotation of said receiving jaws, means engageable with said manually operable means for 45 releasing the wire securing means, and other means engaged by the manually operable means for actuating the wire cutter.

5. In a bundling machine, a frame, a rack, 50 vertically movable means slideable on the frame for elevating said rack, means engageable with the vertically movable means for locking the same in elevated position, a head on the frame, wire holding and twisting means on the head, means for operating the holding and twisting means, other means operable by said operating means subsequently to the twisting of the wire for severing the same from the feeding means, and a 55 trip actuated by the operating means for releasing the rack locking means and permitting the same to move to its lowermost position.

6. In a bundling machine, a frame, a rack, 60 a standard slideable on the frame and sup-

porting said rack, means engageable with the standard for maintaining the same in an elevated position, a trip engageable at times with the means for maintaining the standard in elevated position, a head on the 70 frame, a rotatable twisting jaw journaled in said head, rotatable wire receiving jaws journaled upon the opposite sides of said wire twisting jaw, manually operable means for imparting rotary movement to said twisting 75 jaw and then to said receiving jaws, a wire cutter arranged adjacent one of the receiving jaws and actuated by the manually operable means upon completion of the twisting of the wire, and other means carried by 80 the manually operable means engageable with said tripping means for disengaging the same from the standard and allowing said rack to move to its lowermost position.

7. In a bundling machine, rotatable wire 85 twisting means, rotatable wire receiving jaws arranged adjacent the twisting means, means for rotating said twisting means, other means actuatable thereby for causing said receiving jaws to be rotated slightly 90 upon rotation of said twisting means, and wire securing means engageable with the free end of the wire for holding the same during the twisting thereof, said securing means being engaged by the means for rotating the twisting means whereby to release the wire subsequently to the twisting of the same.

8. In a bundling machine, rotatable wire twisting means, rotatable wire receiving 100 jaws arranged adjacent the twisting means, means for rotating said twisting means, other means actuatable thereby for causing slight rotation of the receiving jaws during rotation of said twisting means, wire 105 securing means adapted to engage and retain the free end of the wire during rotation of said twisting means and to automatically release the same subsequently to the twisting thereof, and means operable subsequently to the twisting of the wire for severing the same from a feed strip.

9. A bundling machine, including, in combination with wire twisting means, a frame, a rack, vertically movable means slideable on the frame for elevating said rack, means engageable with the vertically movable means for locking the same in elevated position, and a trip actuated subsequent to operation of said wire twisting means for releasing 115 the rack locking means and permitting the same to move to its lowermost position.

10. A bundling machine, including, in combination with wire twisting means and means for operating said twisting means, 120 a frame, a rack, vertically movable means slideable on the frame for elevating said rack, means engageable with the vertically movable means for locking the same in elevated position, and a trip actuated by the oper- 125

ating means for releasing the rack locking means and permitting the same to move to its lowermost position.

11. In combination with a bundling machine, wire twisting means thereon including a head, a twisting jaw rotatably mounted in the head, wire receiving jaws rotatably mounted on the opposite sides of said first jaw, a segment mounted in the head 10 and connected to said twisting jaw, an operating handle connected to said segment, trips carried by the operating handle, means operable upon movement of said handle to a predetermined point for imparting rotary motion to said receiving jaws, a pivoted wire securing jaw on the head adjacent one of the receiving jaws, a tapered pin slideable on the head engaged with the pivoted jaw and adapted to be engaged and moved by 20 one of the trips carried on the handle to release said wire receiving jaws at times, and wire cutting means on the head adjacent the opposite wire receiving jaw operable by engagement of the remaining trip on said 25 handle therewith for severing the wire from a feed strip.

12. In combination with a bundling machine, wire twisting means thereon including a head, a twisting jaw rotatably mount-

ed therein, wire receiving jaws rotatably 30 mounted on the opposite sides of said first jaw, a segment mounted in the head and connected to said twisting jaw, a handle connected to the segment, trips carried by said handle, a curved slotted trip pivoted to one 35 side of the head and receiving a portion of the operating arm therein, other segments engaged with said wire receiving jaws, connecting rods engaged at certain of their ends with said segments and having their 40 remaining ends connected to said slotted trip whereby to permit the imparting of rotary motion to the receiving jaws through said last segments, at times, a pivoted wire securing jaw on the head adjacent one of the receiving jaws, a tapered slideable pin on the head engaged with the pivoted jaw and adapted to be engaged and moved by one of the trips carried on said handle to release the same, and wire cutting means on the 50 head adjacent the remaining wire receiving jaw adapted to be engaged by the remaining trip on said handle for severing the wire.

In testimony whereof, I affix my signature 55 hereto.

EDWARD HATCH.

Copies of this patent may be obtained for five cents each, by addressing the "Commissioner of Patents, Washington, D. C."
